AUTOMATIC DRINKING FOUNTAIN

Earl B. Johnson, Freehold, N. J.

Application August 6, 1954, Serial No. 448,351

10 Claims. (Cl. 119—81)

This invention relates to improvements in water fountains and more particularly to drinking fountains of the type illustrated, described and claimed in my co-pending application Serial No. 85,066, filed April 2, 1949, issued March 13, 1956, as Patent No. 2,737,967, and in Patent No. 2,452,305 issued to me October 26, 1948, and in Patent No. 2,662,503 issued December 15, 1953. Each of said patents, the co-pending application and the present application discloses a fountain having an upwardly open container having an outer peripheral vertical wall or edge portion, and a reservoir disposed in the container for up and down movement and providing a water space between said reservoir and container, and having a substantially peripheral marginal lip within the peripheral wall portion, said reservoir preventing flow of water from the container into the reservoir except at the upper part thereof. Said reservoir is of a shape and weight to be buoyed by water in the container when less than a predetermined small amount of water is in the reservoir, and to sink in the water when the reservoir receives a predetermined larger amount of water from the container.

An upwardly pointed water supply jet is mounted in the lower part of the container. Water under pressure from a water supply system is supplied through said jet, and a yieldable sealing disk is secured to and under the axial portion of the reservoir and disposed over and adjacent to said jet and is adapted to rest upon the jet to stop water flow therefrom when the reservoir received enough water therein to cause it to sink.

A loose cover loosely mounted on the container of said patents is disposed over the reservoir and said space to prevent undesired material from falling into the reservoir and said space, and comprises a bowl-shaped intra-marginal part in and spaced from the reservoir, said bowl-shaped part forming a drinking space and being provided near its bottom with an inlet opening communicating with the reservoir.

The general operation of the fountain of Figure 1 is the same as in my patents. When water is drunk from the drinking space, the level in the drinking space and reservoir is lowered until the reservoir floats and raises the disk from the jet, allowing water to flow from the jet over the rim of the reservoir and through the inlet openings of the bowl-shaped part until the reservoir sinks, causing the disk to close the jet, whereupon the operation may be repeated.

An important object of the present invention is to provide means allowing the cover to be removed by hand for cleaning, but preventing the cover from being floated off when the water supply having been cut off is again admitted to the fountain.

Another object is to provide means for eliminating the retarding effect of capillarity and surface tension of the water between reservoir and container without eliminating the centering and lubricating effect of the water held by the surface tension.

Other objects of the invention are to provide a corrosion proof water supply jet, and an efficient and econom-

2

ical guard frame to prevent poultry from getting into the drinking space.

To accomplish the first stated object I have provided an exterior outwardly and downwardly facing annular shoulder face just under said vertical wall of the container, and in the downturned outer loose rim of cover I have provided an inwardly pressed indentation adjacent to said inlet opening and engaging under said shoulder face to prevent the rise of the rim at said indentation, 10 the inlet opening being held down to allow water to enter and sink the cover when the water supply is restored.

To eliminate the undesirable retarding effect of surface tension without eliminating the centering effect I have provided a large number of upwardly and inwardly turned spaced places in the outer periphery of the downturned peripheral lip of the reservoir thereby to present evenly distributed short edge portions to the container at said shoulder face and vertical margin, thus to prevent excess of surface tension between the reservoir and container.

Additional objects of the invention are to effect simplicity and efficiency in such drinking fountains and to provide an extremely simple fountain of this kind which is economical, durable, and reliable in operation, and economical to manufacture and install.

Still other objects of the invention will appear as the description proceeds; and while herein details of the invention are described in the specification and some of the claims, the invention as described in the broader claims is not limited to these, and many and various changes may be made without departing from the scope of the invention as claimed in the broader claims.

In the accompanying drawing showing, by way of example, one of many possible embodiments of the invention,

Fig. 1 is a perspective showing the fountain with guard frame attached;

Fig. 2 is an enlarged axial sectional view of the fountain on the line 2—2 of Fig. 3;

Fig. 3 is a horizontal sectional view on the line 3—3 of Fig. 2;

Fig. 4 is an enlarged sectional view on the line 4—4 of Fig. 2;

Fig. 5 is an enlarged fragmental axial sectional view on the line 5—5 of Fig. 3;

Fig. 6 is an enlarged fragmental sectional view on the line 6—6 of Fig. 3, and

Fig. 7 is a fragmental vertical sectional view through parts of the reservoir and container and through parts of the cover slightly tilted.

My improved drinking fountain comprises principally an upwardly open container 10 and a reservoir 12 similar to those shown in my Patent No. 2,662,503.

The container 10 has an upper deep substantially vertical outer cylindrical peripheral wall portion 14 having long notches 16 in its upper edge, a narrow inwardly downwardly inclined zone 18 just below the portion 14 forming an exterior shoulder face 20, and a downwardly extended inverted frusto-conical lower central portion 22 (Fig. 5) having a lower flat part 24. The frusto-conical portion 22 nests in and has nesting therein similarly shaped strengthening portions 26, 28 also having flat central parts 24a, 24b, the three flat parts having registering openings 23 therethrough.

An upwardly directed slightly upwardly projecting tubular body 30 disposed through said three openings 23 has an upper angular head 32 disposed on said flat part 24, said body 30 having a large diameter threaded portion 34 just below said flat parts and a smaller diameter threaded portion 36 for engagement in a water supply pipe 38. A nut 40 on said large diameter portion serves

for clamping the nut and said head 32 liquid tight against said flat parts 24a, 24b and the flat parts 24, 24a, 24b against each other. Said tubular body has internal threads 42 at the upper end receiving a threaded body 44 of a corrosion-proof stainless steel replaceable jet 46 having a small bore 48 axially therethrough and an angular upper head 50 engaged on said angular head 32 and having an inwardly curved conical face 52 extending to the upper end of the bore 48.

The reservoir 12 is loosely disposed within the container for up and down movement thereon and has at its upper part an outturned peripheral lip 54 having its outer edge 56 adjacent to the said vertical wall portion 14. The reservoir has also an approximately vertical deep upper peripheral portion 58 below said lip, a downwardly pointed lower frusto-conical central portion 60 and a flat bottom 62. Said lip 54 has a large number of equally spaced apart upwardly turned portions 64 spaced away from said vertical wall portion 14 to provide water passage space and to reduce the length of said outer edge 56 to reduce the surface tension and capillary attraction of the water between said edge 64 of the lip and said zone 18 and vertical wall portion 14, without eliminating the centering and lubricating effect of the water held by the surface tension.

Said flat bottom 62 has riveted thereto a clip 66 (Fig. 5) similar to that of Patent No. 2,662,503 and containing a thin disk 68 of rubber or other elastic material exposed through an opening 70 and adapted to rest on the jet 46 to stop water flow when more than a predetermined amount of water is in the reservoir.

A cover 74 over the container has a deep intramarginal bowl 76 forming an upwardly open drinking space 78, and a substantially vertical downturned rim wall 80 loosely surrounding the outer wall portion 14 and shoulder face 20 of the container. The lower part 81 of the wall of the bowl part has an inlet opening 82 to allow water to flow from the reservoir into the drinking space 78. The long notches 16 allow the escape at the loose rim wall 80 of any air that may be trapped in the upper part of the cover.

Said downturned rim wall 80 adjacent to the inlet opening 82 is provided with a horizontally elongated inwardly pressed portion forming an inner lug 84 disposed under the shoulder face 20 to hold down the adjacent side of the cover 74 and prevent the floating off of the reservoir 12 and cover when, after the water supply has been cut off (as for repairs to the water supply system) and substantially all water has been drunk from the cover and reservoir, water is again admitted through the jet. When the water supply is thus restored the side of the cover opposite to the inlet opening 82 and said lug 84 will rise, but the inlet opening will remain down for the inlet of water from the reservoir into the drinking space 78 when the water supply is restored, thus sinking the cover.

The looseness of the rim wall 80 allows the cover to be pivotally raised by hand while pivoting at the lug 84 until the major portion of the rim wall clears the container, whereupon the cover may be removed entirely, 60 for cleaning the fountain or for other purposes.

A guard frame for preventing poultry or other animals from getting into the drinking space is shown in Fig. 1 and includes a substantially stiff slightly resilient wire retaining and supporting ring 88 of inherent inner diameter slightly smaller than the outer diameter of the cover rim wall and having at opposite sides short portions 90 downwardly inclined relative to the adjacent parts of the ring to allow the ring to be slightly straightened at the inclined portions to increase the diameter of the ring enough to allow it to be slipped onto, and held tight on, said rim wall 80.

Arch shaped hoops 92 having upper curved parts crossed and welded, soldered or otherwise secured together at the uppermost part 94, and downwardly ex-

10 tended leg parts 96 secured to equally spaced parts of the ring, to form a cage-like guard to prevent poultry from getting into the drinking space.

15 The various parts of my fountain may be made of brass, copper or other suitable material, but the jet 46 is preferably made of stainless steel.

16 I claim as my invention:

1. In combination, an upwardly open container having a substantially vertical cylindrical outer wall portion and an inwardly inclined shoulder face under said portion; an upwardly open reservoir loosely disposed for up and down movement within the container; a sealing disk on the lower part of the reservoir; a water supply jet projecting upwardly into the container and adapted to be engaged by said disk; and a cover over the container having a substantially cylindrical vertical downturned rim loosely surrounding the outer periphery of the container and having a lug engageable under the shoulder face, said cover having an intramarginal downpressed portion forming a drinking space and having an inlet opening at its lower part on the side of the cover adjacent to said lug.

2. A poultry drinking fountain comprising, in combination, an upwardly open container having a deep substantially vertical peripheral wall portion having a narrow inwardly downwardly inclined zone just below the wall portion forming an exterior shoulder face, and a downwardly frusto-conical lower central portion having a lower central flat part having an opening therethrough; an upwardly open reservoir loosely disposed for up and down movement within the container; a sealing disk on the lower part of the reservoir; a water supply jet projecting upwardly into the container and adapted to be engaged by said disk; and a cover over the container having a substantially cylindrical vertical downturned rim wall loosely surrounding the outer peripheral wall portion of the container and said shoulder face and provided with a lug engageable under the shoulder face; said cover having an intramarginal depressed portion providing a drinking space and having at its lower part on the side of the cover an inlet opening adjacent to said lug.

3. In combination, an upwardly open container having a substantially vertical cylindrical outer wall portion and an inwardly downwardly inclined shoulder face just under said portion; an upwardly open reservoir loosely disposed for up and down movement within the container; a sealing disk on the lower part of the reservoir; a water supply jet projecting upwardly into the container and adapted to be engaged by said disk; a cover over the container having a substantially vertical downturned rim wall loosely surrounding the outer wall portion of the container and said shoulder face and a deep intramarginal bowl forming an upwardly open drinking space; the lower part of the wall of the bowl part having an inlet opening to allow water to flow from the reservoir into the drinking space; said downturned rim wall adjacent to the inlet opening being provided adjacent to said inlet opening with a horizontally elongated inwardly pressed portion forming an inner lug disposed under the shoulder face to hold down the adjacent side of the cover and prevent the floating off of the reservoir and cover when, after the water supply has been cut off and substantially all water has been drunk from the cover and reservoir, water is again admitted through the jet; the inlet opening being held down to allow water to re-enter the reservoir; the looseness of the rim wall allowing the cover to be removed by hand.

4. In combination, an upwardly open container having a substantially vertical cylindrical outer wall portion; an upwardly open reservoir loosely disposed for up and down movement within the container and having an outturned lip having edge parts closely adjacent to said wall portion; a sealing disk on the lower part of the reservoir; and a water supply jet projecting upwardly into the container and adapted to be engaged by said disk; the outer

margin of said lip having a large number of upturned portions to limit the length of said edge parts to reduce the surface tension between the lip and said outer wall portion.

5. In combination, an upwardly open container having a substantially vertical cylindrical outer wall portion and an inwardly inclined zone under the wall portion; a reservoir loosely disposed within the container for up and down movement thereon and having at its upper part an outturned peripheral lip having its outer edge adjacent to the said vertical wall portion and zone; said lip having a large number of equally spaced apart upwardly turned portions spaced away from said vertical wall portion to allow water passage space and to reduce the length of said outer edge to reduce the surface tension and capillary attraction of the water between said edge of the lip and said vertical wall portion without eliminating the centering and lubricating effect of the water held by the surface tension; a sealing disk on the lower part of the reservoir; a water supply jet projecting upwardly into the container and adapted to be engaged by said disk; and a cover over the container limiting upward movement of said upturned parts and having a downturned rim surrounding the outer periphery of the container, and an intramarginal depressed portion forming a drinking space and having an opening in the lower part of its side.

6. In a round poultry drinking fountain having an outer upwardly open container fed by a water jet controlled by means of a reservoir in the container by sink-or-buoyant action, a vertical cylindrical wall on the container having a downwardly facing shoulder; a cover bowl over the container and having a downturned vertical rim loosely surrounding the wall, and an inwardly projecting lug on said rim for engaging under said shoulder, said bowl having an inlet opening adjacent the lug and in the lower part of the cover bowl.

7. A poultry drinking fountain cover bowl and having a cylindrical flange depending from the periphery of the bowl and provided with an internally projecting lug on the flange at the bottom portion thereof, the bowl having an inlet opening in the lower part thereof and near the lug.

8. A poultry drinking fountain cover bowl and having a cylindrical flange depending from the periphery of the bowl and provided with an internally projecting lug on the flange at the bottom portion thereof, the bowl having an inlet opening in the lower part thereof and near the lug, said lug being for engagement under a cylindrical wall of a container over which the cover bowl is adapted to fit loosely.

9. In a poultry fountain having a container with a loosely disposed reservoir therein for controlling a water supply jet in the container, said container having a downwardly facing engagement surface at a peripheral portion thereof, said fountain having a cover bowl provided with a depending lip outer of said shoulder and with an opening in the lower portion of the bowl, the improvement which comprises an inwardly projecting restraining member on the bowl and adjacent the opening for engaging said surface to hold down the bowl on the side having said opening.

10. In a fountain as claimed in claim 9, said cover bowl being pivotable with respect to the container about points of engagement between the member and said surface to permit removal of the cover bowl from the container, the bowl and container being substantially inseparable in closed pivotal position and separable in open pivotal position.
